UNITED STATES PATENT OFFICE.

BARNETT HOROWITZ, OF BROOKLYN, NEW YORK.

HAT-LINING.

1,374,737.

Specification of Letters Patent. Patented Apr. 12, 1921.

Application filed April 1, 1920. Serial No. 370,479.

To all whom it may concern:

Be it known that I, BARNETT HOROWITZ, a citizen of the United States, and a resident of the city of New York, borough of Brooklyn, in the county of Kings and State of New York, have invented a new and useful Hat-Lining, of which the following is a full, clear, and exact description.

This invention relates to hat linings and has for an object the provision of an improved construction wherein the lining may be stitched in by machine and at the same time give the appearance of a usual hand stitched lining.

Another object of the invention is to provide a lining for hats wherein the central part is removably connected to the remaining part of the lining so that it may be placed in position at any time.

A further object more specifically is the provision of a hat lining in which there is provided a substantially annular portion to be stitched in place and a central portion to be clamped in place.

In the accompanying drawing:

Figure 1 is a longitudinal vertical section through a hat showing a lining embodying the invention applied thereto.

Fig. 2 is an elevation of the reverse side of the lining shown in Fig. 1.

Fig. 3 is a fragmentary sectional view through Fig. 4 on line 3—3.

Fig. 4 is a fragmentary sectional view through Fig. 2 on line 4—4.

Fig. 5 is a plan view of the blank of the metal clamp embodying certain features of the invention.

Referring to the accompanying drawing by numerals, 1 indicates a hat of any desired kind and 2 the body of the lining, which is provided with a removable central section 3. The body 2 is made from any kind of cloth with the upper edge 4 turned in as shown in Fig. 1 and then stitched in place by a line of stitching 5, which may be placed in position by a sewing machine, and consequently done at a very low price.

It will be noted that the lining body 2 extends from the brim of the hat to the crown where it is provided with an opening designed to be filled by the central section 3. At the open part of the lining body the material is bent over for forming a tubular edge 6, in which a thread or cord 7 is placed, said thread or cord being preferably non-

stretchable. The central section 3 is provided with a stiffening member 8 of any desired material, as for instance paper or paste-board, said central section being covered with a covering member 9 of cloth, preferably identical with the lining body 2, said covering member 9 overlapping the edges of the stiffening member 8 as shown in Fig. 3. As shown in Fig. 2 the central member 3 is diamond shape, but it may be made round or other shape without departing from the spirit of the invention. At a plurality of points there is provided a fastening member 10, which is formed from a blank 11. This blank is provided with side projections 12 and 13, an end projection 14 and a body 15. The body 15 is passed through the stiffening member 8 and bent over as shown in Fig. 3, while the side projections 12 and 13 are passed through the stiffening member 8 and bent and pressed together as shown in Fig. 4 so as to inclose part of the stiffening member 8 and thereby lock the fastening member 10 in proper position. The end projection 14 is usually bent so as to extend at substantially right angles to the reinforcing member 8 as shown in dotted lines in Fig. 3, until the central section has been placed in position, whereupon they are bent over so as to grip to a certain extent the tubular edge 6, (Fig. 1).

It will be observed from Fig. 3 the covering 9 passes over the clamping ends or projections 12, 13 and 15 so that there will be a finished appearance to the central section co-acting with the finished appearance of the lining body 2. By this construction and arrangement different colored sections 3 could be used without departing from the spirit of the invention, though preferably the same color is provided on this section as is used in body 2.

In manufacturing and placing in position a lining embodying the invention the body 2 is first constructed and stitched to the hat 1 by a machine, though if desired it could be done manually. The section 3 is then provided and the front projections 14 clamped in place whereupon the lining is complete.

What I claim is:

1. A lining for hats comprising a body having an opening in the crown thereof, a substantially non-stretchable member connected to said body adjacent said opening, a central section overlapping said opening, and hook members extending from said cen-

tral section pressing against said non-stretchable member for locking the central section to the body.

2. A hat lining comprising a body having an opening in the crown for substantially the full top thereof, a central member for said opening formed with a stiffening member and a covering member, and clamping hooks extending from said stiffening member over part of the body adjacent the opening for securing the central member to the body.

3. A hat lining comprising a body having an opening in the crown, a central section covering said opening, said central section being formed with a reinforcing sheet and a

covering sheet therefor, and a plurality of bendable clamping members carried by said reinforcing member and adapted to be bent over part of said body adjacent the opening for clamping the central member with the body.

4. A hat lining comprising a body having an opening in the crown and a reinforcing member around the opening, a central section covering said opening, said central section being formed with a stiff back, a cover of ornamental cloth and a plurality of bendable metallic hooks or fingers rigidly secured to said central section, and extending over the reinforcement of said body.

BARNETT HOROWITZ.
